UNITED STATES PATENT OFFICE

148,913

DESIGN FOR A HANDLE FOR A SANDING PAD

Stephen A. Crosby, Chicago, Ill., assignor to Sterling Tool Products Company, a corporation of Illinois

Application October 25, 1946, Serial No. 134,254

Term of patent 14 years

(Cl. D37—1)

To all whom it may concern:

Be it known that I, Stephen A. Crosby, a citizen of the United States, residing at Chicago, county of Cook, and State of Illinois, have invented a new, original, and ornamental Design for a Handle for a Sanding Pad, of which the following is a specification, reference being had to the accompanying drawing, forming a part thereof, in which:

Figure 1 is a side elevational view of the handle member showing my new design; Fig. 2, a top plan view of the same; Fig. 3, a bottom plan view of the handle member; and Fig. 4, an end elevational view of the handle member.

I claim:

The ornamental design for a handle for a sanding pad, as shown.

STEPHEN A. CROSBY.
